UNITED STATES PATENT OFFICE.

CLARENCE F. HALL, OF ATLANTA, GEORGIA.

TRACTION ATTACHMENT.

1,354,826.

Specification of Letters Patent.

Patented Oct. 5, 1920.

Application filed September 2, 1919. Serial No. 321,251.

To all whom it may concern:

Be it known that I, CLARENCE F. HALL, a citizen of the United States, residing at Atlanta, in the county of Fulton and State 5 of Georgia, have invented a new and useful Traction Attachment, of which the following is a specification.

This invention relates to an attachment for automobiles of different types and is 10 designed as a simple and efficient means whereby a motor vehicle can be easily and quickly extracted from mud holes and the like.

The invention is an improvement upon the 15 structure disclosed in my co-pending application Serial Number 294,680 filed May 5th, 1919, and its primary object is to provide means whereby stretching and possible breaking of the device, due to difference in 20 speed of rearward movement of the front and back portions of the attachment at certain times in the operation of the device, is entirely eliminated.

Another object is to simplify and otherwise improve the construction of the device, 25 make it lighter and less expensive than heretofore, and capable of being stowed away in a small space.

With the foregoing and other objects in 30 view which will appear as the description proceeds, the invention consists of certain novel details of construction and combinations of parts which will be hereinafter more fully described and pointed out in the claims, 35 it being understood that various changes may be made in the construction and arrangement of the parts without departing from the spirit or sacrificing any of the advantages of the invention as set forth in the 40 appended claims.

In the accompanying drawings the preferred form of the invention has been shown.

In said drawings—

45 Figure 1 is a side elevation of a motor vehicle having the device in position thereon.

Fig. 2 is a plan view, parts being broken away.

Fig. 3 is a longitudinal section.

50 Fig. 4 is a side elevation of one of the attaching leaves.

Fig. 5 is a face view of one of the attaching yokes and the parts connected thereto.

Fig. 6 is a side elevation of the attaching leaf shown in Fig. 5 and showing its position while releasing the member engaged thereby.

Referring to the figures by characters of reference A and B designate the rear and front sections, respectively, of the attachment. The section A is formed of a length of rope looped at intermediate points to form spaced arms 2 connected by a portion of the rope, as shown at 3, those portions of the rope forming the arms being held together by wrapping them with cord, wire, or other suitable material, indicated at 4. The free ends of the arms 2 form eyes 5 which can be provided with metal reinforcements as shown at 6. The free terminals of 70 the length of rope are formed into eyes 7. A cross strip 8 of canvas or other strong material connects the arms 2 and has terminal eyes 9 slidable on the arms. Thus this strip can be adjusted along the arms to 75 any position desired. Similar strips 10 connect the side portions of the member A and secured to the intermediate portions of these strips 10 is a strip 11 of fabric one end of which is connected to the transverse connecting portion 3 of the rope. The other end of the strip 11 is secured within a slot 12 formed in a yoke 13 shaped to fit transversely upon the tread portion of the tire on one of the rear wheels of a motor vehicle.

Said strip 11 which forms the tread portion of the attachment is longer than the side ropes and is puckered at regulated intervals held in position by cross straps 10 and forms a gully traction, and is form fitting when applied to the wheel. Links 14 extend from the sides of the yoke and are engaged by the eyes. Any suitable means can be provided for attaching the yoke 13 to the wheel. For example a link 15 may be 80 connected to one end of the yoke while the other end of the yoke may be provided with a chain 16 adjustably engaged by a clip 17. By threading the chain between the spokes of the wheel, placing the clip in engagement 85 with the link 15 and tightening the clip, the parts can be securely connected.

The general construction of the front section B is the same as that of section A with the exception that two or more eyes 18 are provided in each of the arms 19 either of which eyes can receive a hook 20 extending from one of the eyes 5. The yoke 21 to which the section B is connected is provided with a chain 22, link 23 and clip 24 similar to those on the yoke 13. The connection between the member B and its yoke is not permanent like the connection between the yoke 13 and section A. Instead short stems 25 are extended from the terminal eyes 26 of the member B and have inturned free ends provided with heads 27. A leaf 28 is hingedly connected to each side portion of the yoke 21 as shown at 29, the axis of movement of each leaf being obliquely disposed relative to the yoke so that, when the leaf is in holding position against or close to the side of the yoke it will be extended toward one edge of the yoke and when in releasing position and extended in the opposite direction, it will project toward the opposite edge of the yoke. These two positions of the leaf have been shown in Figs. 4 and 6. A slot 30 is extended obliquely into each leaf from one edge thereof and these slots are adapted to receive the inturned ends of the stems 25, 30 when the device is applied to a wheel ready for use.

Should it be desired to remove a motor vehicle from a mud hole the rear section A is placed on the ground in front of one of the rear wheels and is connected to the tread portion of said wheel by means of the yoke 13. The yoke 21 is then connected to the tread of the front wheel at a point close to the ground and back of the point of contact between the wheel and ground. The leaves 28 are moved to the positions shown in Fig. 4 and the inturned ends of the stems 25 are slipped into the slots 30. Section B is then placed around the wheel and the arms 19 are located at opposite sides of the point of contact between the wheel and the ground. The two sections A and B are then connected by the hooks 20. By applying power to the rear wheel it will move onto the section A and wind said section upon the wheel. At the same time said section will pull on section B which will bind under the front part of the base of the front wheel and hold steady, by the weight of the vehicle against the ground, enabling the rear wheel to wind up onto said section A and raise itself out of the mud hole or the like, and move forward and cause it to unwind from the front wheel, thereby causing said wheel to rotate. As the yoke 21 reaches the lowest point during its rotation and begins to move upwardly at the back of the front wheel the rear wheel will pull on the sections A and B faster than they will be paid out by the front wheel. In order to prevent the sections from stretching or

breaking as a result of this condition, the leaves 28 have been mounted in the peculiar manner described and shown. Accordingly, during the upward movement of the leaves 28 after passing under the wheel, said leaves 70 will swing laterally and rearwardly, as shown in Fig. 6, thereby compensating for the difference in movement at the front and rear ends of the attachment and at the same time allowing the stems to slide freely from 75 the slots and thereby disengage the section B from the front wheel. If, when applying the attachment to the wheels it is found that it is necessary to travel farther than one revolution of the wheels, a third section (not 80 shown) and which is similar to section B, can be joined on to section B, by hook 20 at the point where section A is to be connected under ordinary conditions. The third section then is to be wound around the front wheel 85 over the top of section B in the same manner, and connected to section A as section B would have been connected under ordinary conditions, thereby forming an intermediate section which extends the length of the attachment and allows a longer travel thereon. 90

What is claimed is:—

1. A device of the class described including detachably connected front and rear sections, means for securing the rear section to the rear wheel of a motor vehicle, obliquely mounted hinged members, means for connecting them to the front wheel of said vehicle, and means for detachably connecting the front section to said members. 95

2. A device of the class described including detachably connected front and rear sections, means for securing the rear section to the rear wheel of a motor vehicle, and a connecting structure for attaching the front section to the front wheel of said vehicle, said structure including movable means for compensating for the difference in rearward movement of the sections and the speed with which they are paid out by the front 100 wheel. 105

3. A device of the class described including detachably connected front and rear sections, means for securing the rear section to the rear wheel of a motor vehicle, a yoke, means for detachably connecting the yoke to the front wheel of said vehicle, obliquely disposed leaves hingedly connected to the side portions of said yoke and having inclined slots therein, and means on the front section 115 of the device for engagement with the slotted leaves to detachably connect the yoke and front section. 120

4. A device of the class described including a front wheel engaging section, means for attaching one end thereof to the front wheel, a section for attachment to the rear wheel, means for connecting the sections adjacent the base of the front wheel, each section including a length of rope looped to 125 130

form spaced arms at one end connected by an intermediate portion of the rope, cross strips connecting the side portions of each section, and a longitudinally extending strip 5 spaced from the side portions of the rope and secured to said cross strips, and to said intermediate portion.

In testimony that I claim the foregoing as my own, I have hereto affixed my signature in the presence of two witnesses.

CLARENCE F. HALL.
